UNITED STATES PATENT OFFICE.

EVERETTE ALLEN AND FLOYD ALLEN, OF CLARE, MICHIGAN.

ROAD AND DITCH MACHINE.

Application filed September 26, 1921. Serial No. 503,266.

To all whom it may concern:

Be it known that we, EVERETTE ALLEN and FLOYD ALLEN, citizens of the United States of America, residing at Clare, in the county 5 of Clare and State of Michigan, have invented certain new and useful Improvements in Road and Ditch Machines, of which the following is a specification.

Our present invention relates generally to 10 road and ditch machines, and more particularly to a scraper of that type embodying a flat body, our object being the provision of a scraper which can be operated with minimum power in hard ground and which may 15 be used with equal facility in soft, mucky or hard uneven surfaces. A further object is the provision of a flat scraper having means by which, when loaded the scraper may be simply released by the operator and will 20 carry its load to the point of disposition and a still further object is the provision of a scraper of this type having a strong self-sharpening blade.

In the accompanying drawing which illustrates 25 our present invention and forms a part of this specification,

Figure 1 is a perspective view looking from the front of our improved scraper,

Figure 2 is a perspective view looking 30 from the rear thereof, and

Figure 3 is a longitudinal section taken substantially on line 3—3 of Figure 1.

Referring now to these figures we provide 35 a scraper including a flat body 10 consisting for instance of a series of transversely disposed planks in edgewise contacting relation, secured by battens along its rear or undersurface, certain of which may be metal battens 11 as seen in Figure 2 and certain 40 of which may be wooden battens 12, to the latter of which the beams 13 of handles 14 are connected.

The handles 14 preferably curve rearwardly beyond the upper rear edge of the 45 body 10, the latter of which has laterally extended portions 15 adjacent to its opposite edge and is provided with a blade 16 extending along and beyond said last mentioned edge and along the laterally extended 50 portions 15, it being noted that this blade is transversely curved throughout its length to provide a forward concave face so that its edge 17 will be self-sharpening as it is dragged over the ground, particularly hard 55 soil.

Side rails 18 are also employed in spaced parallel relation to the side edges of the flat body 10, the lower forward ends of which rails are securely fastened to the laterally extended portions 15 of the body. The rails 60 have their opposite ends inturned as at 19 secured to the upper or rear side portions of the body 10. These side rails brace the extended portions 15 and also serve as guards for the draw bars 20 the latter having forward and 65 downwardly inclined portions at the front of the scraper and rear curved portions extending between the side edges of the body and the rails 19 with their rear ends securely fastened to the rear surfaces of the 70 laterally extended portions 15 so that the pull through the draft chain 21 whose opposite ends are engaged with the forward ends of the draw bars 20 will be communicated directly to the opposite ends of the blade 16. 75

In addition to the foregoing features the flat scraper provided by our invention has rear runners 22, each in the nature of a substantially semicylindrical shoe formed of a bent plate whose opposite ends are flanged 80 and securely fastened at longitudinally spaced points upon the rear surface of the flat body 10 adjacent to opposite sides of the body and near its lower forward blade carrying edge. 85

In use our improved scraper is such as to render it comparatively easy to cut and move hard ground as well as to regulate the exact depth of cut with the handles 14. When the scraper in use is loaded it is also a simple easy matter to tilt the same back on the 90 runners and then release the handles whereupon the scraper will carry the load to a desired point of disposition even up steep inclines by virtue of the character and disposition of the runners. 95

Our improved scraper may be utilized in manly instances in soft as well as hard surfaces where the scrapers now employed are of little value and by curving the blade at the 100 lower portion of the flat body we provide for greater strength and for self-sharpening of the cutting edge.

We claim:

A road scraper having a flat body provided with laterally extended portions at its front edge, a blade secured along the said front edge of the body and along the said extended portions thereof, rails spaced from the side edges of the body, having inturned 110

upper ends secured to the body and having
their lower ends connected to the said ex-
tended portions, draw bars extending for-
wardly from opposite sides of the body hav-
ing rear curved portions extending between
the sides of the body and said rails, secured
at their ends to the said extended portions of

the body, runners upon the rear of the body,
and handles secured to the body and project-
ing rearwardly beyond the same as described. 10

In testimony whereof we have affixed our
signatures.

EVERETTE ALLEN.
FLOYD ALLEN.
